DESIGN FOR A UTILITY TABLE

Joseph R. Corbett, Sharonville, Ohio, assignor to
NuTone Chimes, Inc., New York, N. Y., a cor-
poration of New York

Application February 10, 1942, Serial No. 105,748

Term of patent 7 years

To all whom it may concern:

Be it known that I, Joseph R. Corbett, a citizen of the United States, residing at Sharonville, in the county of Hamilton and State of Ohio, have invented a new, original, and ornamental Design for a Utility Table, of which the following is a specification, reference being had to the accompanying drawing, forming a part thereof.

Figure 1 is a perspective view of the utility table, showing my new design.

Figure 2 is a side elevational view.

Figure 3 is an end elevational view.

Figure 4 is a perspective view showing the table of the design arranged for reading purposes.

I claim:

The ornamental design for a utility table, substantially as shown.

JOSEPH R. CORBETT.
